US00D487445S

(12) **United States Design Patent** (10) Patent No.: **US D487,445 S**
 (45) Date of Patent: ** Mar. 9, 2004

(54) **CORDLESS TELEPHONE**

(75) Inventors: **Hartmut Heinrich Esslinger**, Sunnyvale, CA (US); **Howard Geoffrey Nuk**, Sunnyvale, CA (US); **Kevin Christian Coullahan**, Sunnyvale, CA (US); **Jon Christopher Lake**, Sunnyvale, CA (US); **Michael J. Slipy**, Fort Lauderdale, FL (US)

(73) Assignee: **Disney Enterprises, Inc.**, Burbank, CA (US)

(**) Term: **14 Years**

(21) Appl. No.: **29/160,074**

(22) Filed: **May 3, 2002**

(51) LOC (7) Cl. **14-03**

(52) U.S. Cl. **D14/147**; D14/148

(58) Field of Search D14/137, 138, D14/218, 147-151, 247-249, 251-253, 144, 240, 242, 341-347, 399, 426, 387, 429, 453, 197, 198, 189, 192, 193, 157, 194, 195, 196, 158; 379/433.01-433.13, 434, 419, 420.01-420.04, 428.01-428.02, 440, 435, 436; 455/550.01-90.3; D13/168; D18/2, 7; D21/517, 329, 331, 333; D10/104, 106, 65; 381/86
